CIRCULATING SYSTEM FOR RETREADING
MOLD PRESSURE BAGSHerbert J. Wock, Lodi, Calif., assignor to Super
Mold Corporation, Lodi, Calif., a corporation

Application April 21, 1931, Serial No. 531,729

5 Claims. (Cl. 18—18)

This invention relates to tire retreading with the use of the full-circle mold such as that shown in my Patent No. 1,764,378, dated June 17, 1930; and particularly represents improvements over 5 the structure for filling and retaining a pressure bag full of water and under pressure, shown in my co-pending application for patent, Serial No. 519,411, filed March 2, 1931.

One of the objects of the present invention is 10 to provide a system of the above character and for the same purpose which eliminates the need of a pressure pump (which is a somewhat expensive piece of apparatus and is apt to leak and give trouble) and substitute therefor a simple 15 circulating pump.

Another object of the present invention is to provide a centralized control for the system, or in other words one so arranged that water may be forced into the bag, discharged therefrom, or 20 permitted to circulate through the pump and the heating tank without entering the bag, by the proper manipulation of a single valve.

A further object of the invention is to produce 25 a simple and inexpensive device and yet one which will be exceedingly effective for the purpose for which it is designed.

These objects I accomplish by means of such 30 structure and relative arrangement of parts as will fully appear by a perusal of the following specification and claims.

In the drawings similar characters of reference indicate corresponding parts in the several views:

Fig. 1 is a diagrammatic elevation of my improved circulating system.

Fig. 2 is a sectional elevation of a six-way valve 35 preferably used to effect the desired centralized control of the system showing the valve plug in its neutral position.

Figs. 3 to 5 are cross sections of the valve taken 40 on the lines 3—3, 4—4 and 5—5 respectively of Fig. 2; showing the valve plug in the position occupied when water is being circulated through the tire bag.

Figs. 6 to 8 are similar sectional views of the 45 valve showing the positions of the plug when the water is exhausted from the bag and its place taken by air.

Figs. 9 to 11 are similar sections of the valve 50 showing the plug in its neutral position or when the water is merely being circulated between the pump and the tank.

Fig. 12 is a sectional elevation of a special form of bag-stem and water intake member.

Referring now more particularly to the characters of reference on the drawings, 1 denotes

one of the continuous circular sections of a retreading mold, in which the tire 2 is mounted. The pressure bag 3 is placed inside the tire, which is engaged by a rim 4 which prevents the sides of the tire from spreading and also confines the bag in place. Steam to heat the mold chamber is generated in the usual manner, by an apparatus which has nothing to do with the present invention.

The water heating and circulating system for 10 the bag comprises a suitable steam generating boiler 5. A steam coil 6 is connected to the boiler so that a continuous circulation of steam will be had through the coil. A water tight tank 7 surrounds the coil so that the water in the tank will 15 be heated by the heat in the coil.

To maintain the water in the tank at a constant temperature, by reason of the temperature of the steam in the coil, I provide an automatic 20 thermostatic control device 8 connected to the tank and to the burner R of the boiler 5. A pipe 9 leading from a source of compressed air located at a point remote from the system is connected to the top of the tank. The pressure in the pipe is constant, and is maintained at a pressure 25 sufficient to prevent the generation of steam from the water in the tank when said water is heated to the high temperature necessary for the purpose.

10 designates the casing of a special six-way 30 valve, in which the plug 11 is turnably mounted. A handle 12 applied to one end of the plug controls its turning, while a pawl arm 13 is pivoted on the handle and has a nub 14 attached to engage a notch flange 15 on one end of the casing. 35 The notches in this flange are spaced so that the plug may be held in any one of three predetermined positions. The casing has opposed pairs of ports A and D, B and E, C and F. The port A is connected to the bag 3 at the bottom by a 40 pipe 16; port B is connected to the top of the tank 7 by a pipe 17; and the port C is connected to the bottom of the tank by a pipe 18. The port D is connected to the discharge of a circulating 45 pump 19 by a pipe 20; the port E is connected to the bag at the top by a pipe 21; while the port F is connected to the intake of the pump by a pipe 22.

The plug 11 is provided with a plurality of 50 passages 23, 24 and 25 to register with the ports A and D, B and E, and C and F respectively. These are so arranged that upon turning the plug to a certain position, the water may be fed into the bag and circulated therethrough while being 55

maintained at a predetermined pressure. This result is obtained as follows:

The water may pass from the pipe 18, through the valve ports C and F and plug passage 25 to the intake of the pump through the pipe 22; from the discharge of the pump through the pipe 20 back to the valve, and from the valve to the bag through the pipe 16 by means of the ports A and D and plug passage 23. At the same time a return circulation is had through the pipe 21, the valve by means of the ports E and B and the plug passage 24, and the pipe 17 back to the top of the tank. The position of the plug in the valve body to give these results is shown in Figs. 3, 4 and 5. The air pressure from the pipe 9 being constantly on the water in the tank, the water in the pipe and bag are held at whatever pressure is desired. Not only is the water in the bag held at this pressure, but the water which is heated to a relatively high temperature by contact with the steam coil, is kept from turning into steam. The valve plug is left in the above position, to permit of and continue circulation of the water, as long as a retreading operation is in progress.

When it is desired to empty the bag the valve plug is turned to a position which gives the following circulation of the water. The water from the tire passes to the valve through the pipe 16 and leaves the valve through the pipe 22. This is done by means of a bypass 26 in the valve body leading from the pipe 16 to a port G in said body in alinement with the plug passage 25, which then registers with said port and the port F. The water then passes to the pump and circulates through the pump back to the valve through the pipe 20. The water then passes from the valve back to the tank through the pipe 18. This is done by means of another bypass 27 in the valve body leading from a port H in the body in alinement with the plug passage 23 and extending to the pipe 18; the passage 23 then being positioned to place the plugs D and H in communication. At the same time the compressed air flows from the tank through the pipe 17 and passes through the valve into the top of the bag through the pipe 21 by way of the ports B and E and the plug passage 24. The bag is thus completely emptied of water to allow the same to be removed from the tire and mold; the water being replaced by air. This positioning of the plug is shown in Figs. 6, 7, and 8.

While the bag is being removed from one tire and subsequently inserted in another, the water may be reheated and circulated through the tank by moving the valve plug to the third position. This also shuts off the flow of air to the bag so that the air now in the bag can be exhausted to the atmosphere without the need of any other shut off valves at the bag connections. This results in the water passing from the tank to the valve and thence to the intake of the pump through the pipes 18 and 22, respectively, by means of ports C' and F and the plug passage 25. At the same time water flows from the discharge of the pump through the valve to the top of the tank by way of the pipes 20 and 17. This is done by means of a bypass 28 in the valve body leading from a port J in said body in alinement with the plug passage 23 to the pipe 17; the plug passage 23 then establishing communication between the ports D and J. The passage 24 then breaks communication between the pipes 17 and 21 so that the air is shut off from passing to the bag. This positioning of the plug is shown in Figs. 9, 10 and 11. In this manner the water is

kept out of the bag and is reheated to an even degree by its circulation about the steam coil. If it is not desired to circulate the water when the valve plug is set in this position it is of course only necessary to halt the operation of the pump.

In connection with the above described water circulating system, I have found that it is very essential for proper results, that the water be delivered to the bag near the bottom and in all directions. To accomplish this and to also enable the same water intake tube to be used with all sizes of bags, I have provided the special arrangement shown in Fig. 12.

In this structure a tubular stem 29 is rigidly secured to and projects outwardly from the inner periphery of the bag in the same manner as the usual air valve is secured to the inner tube of a tire. The water intake tube 30, of a length sufficient to project to the bottom of a bag of any size which may be used is slidable through the stem. On its inner end the tube is provided with a bottom hole and other holes 31 all about the adjacent portion of the tube. On its upper end the tube carries an elbow 32, to which a length of flexible hose 33 leading from the pipe 16 is detachably connected in the usual manner.

Slidable on the tube is a sleeve 34 having a downwardly projecting flange 35 at the bottom which is turnably engaged by a nut 36 detachably threaded on the upper end of the stem 29. The outer end of the stem and the adjacent bore of the sleeve 34 are beveled as at 37 so as to have wedging engagement with each other.

The upper portion of the sleeve is provided with suitable packing 38 engaging the tube, which is compressed thereabout by a nut 40 screwed into the sleeve. The nut is split on one side and is provided with a transverse clamping pin 41 so that the nut may be clamped against the tube to hold the latter immovable. The nut 36 is turned by opposed handle rods 42, connected thereto, while the sleeve 34 also has a radial handle rod 43 to prevent said sleeve from turning when the nut is being screwed down. The stem 29 is the only part which is permanently mounted on any bag, the remaining parts being separate and applicable to any stem and bag.

In applying the tube 30 to any bag, it is slid into place through the stem 29, and the nut 36 is then turned down so as to clamp the surfaces 37 against each other; the handle 43 being held by the operator during this movement of the nut so as to prevent any rotation of the sleeve. The tube 30 is then pressed down until it touches the bottom of the bag and is then retracted about one-eighth of an inch or so. It is then held in this position while the packing nut 40 is clamped down hard against the packing. The clamping pin 41 is then actuated so as to pinch the nut against the tube and thus hold the latter in the position to which it has been set, as above described. The flexible hose may then be coupled to the elbow 32 and the water circulated through the bag.

It is to be understood that while I have specified water as being the liquid preferably used, other liquids such as oil, glycerine or the like are capable of being used instead. It is also to be understood that while I have shown and described the system as being designed for use in connection with a retreading mold, it is capable of being used with a tire making mold as well.

From the foregoing description it will be readily seen that I have produced such a device as

substantially fulfills the objects of the invention as set forth herein.

While this specification sets forth in detail the present and preferred construction of the device, 5 still in practice such deviations from such detail may be resorted to as do not form a departure from the spirit of the invention, as defined by the appended claims.

Having thus described my invention what I 10 claim as new and useful and desire to secure by Letters Patent is:

1. An apparatus for vulcanizing rubber on a tire casing comprising a system to circulate liquid through the casing, such system including a liquid supply tank, means to admit a gas under pressure into the tank, means affording communication between opposite ends of the tank and diametrically opposed inlets into the casing, a 15 circulating instrumentality interposed at a point in the system, and a single manually controlled valve interposed in the system and operable to selectively permit the circulation of liquid from the tank through the casing in a continuing cycle, the interruption of such cycle and the 20 return of the liquid to the tank, and the replacement for the liquid in the casing of gas under pressure.

2. An apparatus for vulcanizing rubber on a tire casing comprising a system to circulate liquid through the casing, such system including a liquid supply tank, means to admit a gas under pressure into the tank, means affording communication between opposite ends of the tank and diametrically opposed inlets into the casing, 25 a circulating instrumentality interposed at a point in the system, and means to selectively effect the circulation of liquid from the tank through the casing, the return of the liquid to the tank and the replacement therefor in the 30 casing of gas under pressure, and the circulation

of the liquid from the tank through the circulating instrumentality and back to the tank without moving it through the casing.

3. An apparatus for vulcanizing rubber on a tire casing comprising a system to circulate liquid through the casing, such system including a liquid supply tank, means to admit a gas under pressure into the tank, means affording communication between opposite ends of the tank and diametrically opposed inlets into the casing, 10 means to selectively effect the circulation of liquid from the tank through the casing while maintaining it under the influence of the gas pressure and to discharge the liquid from the casing and return it to the tank while replacing it 15 with gas under pressure.

4. An apparatus for vulcanizing rubber on a tire casing including a tank to hold water, means to maintain a constant gas pressure against the water in the tank, means to heat the water, 20 means to circulate the heated water in one direction through the casing while maintaining the gas pressure thereon, and means to withdraw the water from the casing and at the same time substitute the gas under pressure for the water with- 25 in the casing as the latter is withdrawn therefrom.

5. An apparatus for vulcanizing rubber on a tire casing including a tank to hold water, means to maintain a constant gas pressure against the 30 water in the tank, means to heat the water, means to circulate the heated water in one direction through the casing while maintaining the gas pressure thereon, means to withdraw the water from the casing and at the same time substitute 35 the gas under pressure for the water within the casing as the latter is withdrawn therefrom, and means to shut off communication between the casing and both the water and gas.

HERBERT J. WOOCK.
